UNITED STATES PATENT OFFICE.

GEORGE A. BLANCHARD, OF MALDEN, MASSACHUSETTS.

SKIRT-PROTECTOR.

SPECIFICATION forming part of Letters Patent No. 275,014, dated April 3, 1883.

Application filed January 15, 1883. (No model.)

To all whom it may concern:

Be it known that I, GEORGE A. BLANCHARD, of Malden, in the State of Massachusetts, have invented an Improved Skirt-Protector, of which 5 the following is a specification.

The object of this invention is the protection of ladies' dress and underskirts in stormy weather, or when the streets are muddy or dirty; and it consists in the construction and 10 combination of the divers devices or parts embodied therein, as will, in connection with the accompanying drawings, be hereinafter fully described, and specifically defined in the appended claims.

15 Figure 1 shows my invention in longitudinal vertical section and as supported upon a lay-figure. Fig. 2 shows my invention in perspective, with a portion of the outer and inner wall broken away to show its construction. 20 Fig. 3 is a detached perspective view, showing a portion of the inner wall and hoop, the supporting-strap attached to said wall, and the band for attachment to the limb of the wearer. Fig. 4 represents my invention, in perspective, 25 as being worn by a lady, also shown in perspective.

In said views, *a* represents the skirt proper, which should, for use in stormy weather, be made of the well-known gossamer rubber cloth 30 or other water-proof material, but which may, for use when the weather is fair but the streets foul, be formed of linen or other suitable material not water-proof. This skirt is formed of the usual fullness from the waist downward 35 to the point marked *b*, from whence it is contracted in its circumference to form the pocket *c*, to be arranged inside of part *a*, as shown in Figs. 1 and 2. An elastic hoop, *e*, is secured to the edge of pocket *c*, as shown, and two or 40 more straps, *f*, are secured to said pocket, adjacent to said hoop *e*, as shown in Fig. 3. These straps are arranged to be secured to bands *g* by a ring and hook, as shown, or by other means, and said bands are secured to the limbs of the 45 wearer, as shown in Fig. 1. From point *b* a flounce, *d*, of the requisite fullness, descends the proper distance, as shown.

The application and operation of my invention are as follows: The intending wearer, being 50 dressed, will place this skirt over her dress and secure it at the waist in any desired manner. Then pocket *c* is raised up inside the skirts

of the dress and under-clothing, and is secured in such position by means of bands *g* or other means, the skirts of the dress and under-cloth- 55 ing (marked *h*) falling naturally, and without care of the wearer, into the space between skirt *a* and pocket *c*, as shown.

Instead of using the bands *g*, secured to the limbs of the wearer, the pocket *c* may be se- 60 cured and supported by straps depending from a band secured to the waist, or by straps de- pending from the shoulders; and the skirt *a*, pocket *c*, and flounce *d* may all be formed sepa- 65 rately and united together at *b*, if desired; but the flounce should in all cases, whether 70 the skirt *a* is formed of water-proof material or not, be formed of or faced upon the inside with water-proof material, for the purpose of cleaning off the mud that may be communi- 75 cated thereto by the feet of the wearer, with- out saturation of the flounce.

My protector may be united with a waist, so as to form an entire outer dress; but it is usually found preferable to have it extend only 75 to the waist of the wearer, where it can be se- cured in any desired manner.

By reason of the elasticity of hoop *e*, usu- 80 ally formed of the well-known "hoop-skirt wire," my protector can be folded into a very small space, and carried in a small hand-bag or satchel, ready for use at all times; and it can be quickly donned, as no removal of any of the clothing is requisite for that purpose, and when worn all the skirts of the wearer are 85 protected, not only from falling rain, but from the wet and dirt of the street, or the usual effect of contact with the shoes of the wearer.

I am aware that it is common to make and wear a double skirt, one end or extremity of which 90 is first secured to the waist of the wearer, inside of all the usual underskirts, after which said underskirts and the dress are donned, when the opposite end of the protector is brought up outside of the dress and secured 95 at the waist, and I make no claim thereto, my protector being so constructed that it can only be applied after the dress and all the under- clothing are in position upon the wearer, and it can be so applied without removal of any 100 part of the clothing.

I claim as my invention—

1. A skirt-protector formed with exterior part, *a*, and the interior hooped pocket, *c*, the latter

secured at one of its edges to part *a*, and arranged to form, when its free edge is raised and supported, a concentric receptacle for the dress and under skirts *h*, substantially as specified.

5 2. In a skirt-protector, the combination of skirt *a*, flounce *d*, pocket *c*, and elastic hoop *e*, substantially as specified.

3. In a skirt-protector, the combination of skirt *a*, having the extension or flounce *d*, pocket

c, secured to said skirt, elastic hoop *e*, secured to the free edge of said pocket, and straps *f*, for supporting such free edge of the pocket, substantially as specified.

GEORGE A. BLANCHARD.
